UNITED STATES PATENT OFFICE.

MATTHEW GRISWOLD, JR., OF ERIE, PENNSYLVANIA.

DESIGN FOR A STOVE-DAMPER HANDLE.

SPECIFICATION forming part of Design No. 32,881, dated June 26, 1900.

Application filed May 16, 1900. Serial No. 16,933. Term of patent 14 years.

To all whom it may concern:

Be it known that I, MATTHEW GRISWOLD, Jr., a citizen of the United States, residing at Erie, in the county of Erie and State of Pennsylvania, have invented and produced a certain new and original Design for Stove-Damper Handles; and I do hereby declare the following to be a full, clear, and exact description of the invention, such as will enable others skilled in the art to which it appertains to make and use the same, reference being had to the accompanying drawing, and to the letters of reference marked thereon, forming part of this specification.

15 The leading feature of my design consists in the shape and configuration of a stove-damper handle; and it consists, substantially, in a head in the shape of a spread-eagle with an arch resting upon the points of the extended wings, the eagle resting upon the end of the spindle of the stove-damper, so as to form the handle portion thereof.

20 The figure is a view in elevation of a stove-damper spindle with a handle thereon embodying my design.

25 In the drawing, A is the cylindrical stem or

body of a stove-damper spindle, having lugs a on opposite sides thereof and terminating in a conical point a' at one end and at the other in a collar a'' , which forms a pedestal, 30 upon which the feet d and tail portion d' of a spread-eagle D rest. The wings E E of the eagle D spread laterally to the right and left, and resting upon the outer ends of the wings are the scroll-shaped ends f of an arch-shaped 35 piece F, the center of which is also ornamented with scrollwork f' , under which the head C of the eagle D extends upward from the body thereof, and upon the central part of the body of the eagle D there is a shield 40 G, upon which stars and stripes are portrayed.

Having thus described my design, what I claim is—

The design for a stove-damper handle, substantially as shown and described.

45 In testimony whereof I affix my signature in presence of two witnesses.

MATTHEW GRISWOLD, JR.
